[57] CLAIM

The ornamental design for a combined portable hydraulic pump and integral carrying case, as shown and described.

DESCRIPTION

FIG. 1 is a top, front and right side perspective view of a combined portable hydraulic pump and integral carrying case, showing my new design;

FIG. 2 is a left side elevational view thereof;

FIG. 3 is a top plan view thereof, the bottom being identical in appearance;

FIG. 4 is a front end elevational view thereof; and,

FIG. 5 is a rear end elevational view thereof.
